(57) **CLAIM**

I claim the ornamental design for medical patient pants, substantially as shown and described.

DESCRIPTION

FIG. 1 is a perspective view of medical patient pants showing the new design;

FIG. 2 is a front view of medical patient pants showing the new design;

FIG. 3 is a rear view of medical patient pants showing the new design;

FIG. 4 is a side view of medical patient pants showing the new design;

FIG. 5 is an opposing side view of medical patient pants showing the new design;

FIG. 6 is a top view of medical patient pants showing the new design;

FIG. 7 is a bottom view of medical patient pants showing the new design; and,

FIG. 8 is a perspective view of medical patient pants showing the new design with one of the zippers open.

The dash-dot broken lines define boundaries that form no part of the claim. The evenly dashed broken lines illustrate stitching that forms no part of the claim.

1 Claim, 8 Drawing Sheets
